In Germany June 4, 1935

2 Claims. (Cl. 128—395)

Our invention relates to electric irradiators.

It is an object of our invention to provide a preferably portable electric irradiator which is particularly suitable for therapeutic purposes.

5 To this end, we use electrodes designed for a minimum current density of 0.26 amp. per square millimetre of electrode cross-sectional area, and we arrange a core in each electrode of such composition that a spectrum like the sun's is produced. The core may be of pure metal, or metal oxide, or a metal salt, or of a combination of any 10 two, or all, of the said substances. According to our invention, the two electrodes are arranged to include an acute angle, and one of them may 15 be parallel to, and preferably at a short distance from, the optical axis of a reflector. Electrodes of the type referred to are old in this art, and it has also been proposed to operate them, by way of investigation, with current densities of the order 20 aforesaid. However, in the apparatus employed for such investigations, the electrodes are aligned axially and the arc burns in a closed-up arc chamber.

In our radiator, on the other hand, atmospheric 25 oxygen is freely admitted to the arc.

In order to obtain a burning period of adequate duration with axially aligned electrodes whose arc is not enclosed in an arc chamber, an automatic electrode feeding mechanism would be required 30 which would not only increase the cost of the irradiator but would also render it unsuitable for operation by unskilled persons. We overcome these difficulties by arranging the—highly loaded—electrodes at an acute angle to each other. 35 In this manner, adequate burning periods are obtained without the automatic feeding mechanism referred to, i. e., with the electrodes being stationary during burning.

As compared with electrodes arranged in parallel 40 relation to, and at a short distance from, each other, our angularly arranged electrodes have the advantage that the arc is extinguished automatically after a predetermined time. Therefore, our irradiator is entirely foolproof and it cannot occur that a careless or unskilled operator allows the electrodes to burn down to the sockets, a risk 45 which is always present with electrodes arranged in parallel relation. As mentioned, one of the electrodes may be parallel to the optical axis of the reflector, but still the other electrode is at an acute angle to the first electrode.

It is another object of our invention to provide a self-contained and readily portable unit on which all parts required for its operation are assembled.

To this end, we provide a transformer on the irradiator and connect the transformer to a normal, preferably a. c., electric lighting system on the one hand, and to the electrodes on the other hand. By these means, notwithstanding the connection of the transformer to a normal system, so much energy is produced that the irradiator is very efficient.

It is another object of our invention to produce a maximum illuminated area of practically uniform light intensity. To this end, we build up our reflector from a set of plane sector-shaped mirrors arranged concentrically to the optical axis of the reflector, and at an angle to each other.

By arranging one of the electrodes in parallel 15 relation to, and at a short distance from, the optical axis of the reflector and the other at an acute angle to this electrode, uniform intensity of the illuminated area is obtained independently 20 of the burning-down of the electrodes.

For the same purpose the mirrors of the reflector are made with non-reflecting areas, and the size of the areas is increased toward the reflector axis.

By these means, we obtain a readily portable 25 and self-contained irradiator whose construction is so simple that it can be operated by non-skilled persons. It is understood that our invention is not limited to portable apparatus of the kind referred to, but may also be adapted to stationary 30 irradiators if desired.

In the accompanying drawings, a portable irradiator embodying our invention is illustrated more or less diagrammatically by way of example.

In the drawings

Fig. 1 is a side elevation, partly broken open, and

Fig. 2 is an end elevation of the irradiator, viewed from the left in Fig. 1.

Fig. 3 shows part of the irradiator in section on line III—III in Fig. 2.

Fig. 4 is an elevation of an electrode for the irradiator, partly broken open to expose its core.

Fig. 5 is an end elevation, viewed as in Fig. 2, and Fig. 6 is a section on the line VI—VI in Fig. 5, 45 of a reflector whose mirrors define slots with sides diverging toward the optical axis of the reflector, and

Fig. 7 is an end elevation of another reflector whose mirrors define holes whose size increases 50 toward the optical axis of the reflector.

Referring now to the drawings, 1 is the base, or transformer casing, of the irradiator, and 19 is a transformer in the casing, with a conduit 20 for connecting the primary coil of the transformer 55

to a normal, for instance, 220 volt, lighting system.

A handle 4 for carrying the irradiator is secured to the top plate of the transformer casing 1, and a pin 7 is inserted in a bore in the front portion 5 of handle 4, and held by a set screw 6. The upper end of the pin has a fork 8 with a pivot 9, and a wing nut 11 on the pivot. A bracket 10 on a reflector casing 2 is inserted between the 10 arms of the fork 8 and placed on the pivot 9.

At its outer end, the reflector casing 2 is open, so that atmospheric oxygen has free access to the arc between the electrodes 26 and 27, as against the closed-up air chamber referred to. On its 15 upper portion, the reflector casing 2 is equipped with a ventilator 13 having slots 12. Hinged to its inner end at 14, and secured by a swing bolt 16, a nut 17, and a slotted member 18, is an electrode cowl 3. At its inner end, the cowl 3 is 20 equipped with a dished bottom plate 22, preferably of heat-insulating material, with holes 23 through which the electrodes 26 and 27 project into the reflector casing 2. Secured on the bottom plate 22 is a frame 3' in the cowl 3. The 25 holder 25 for the electrode 27 is secured on a flange 3'' of the frame which projects through the lower hole 23. By these means, the electrode 27 is held in a fixed position with respect to the reflector 28 during the operation of the irradiator. 30 The holder 24 for the electrode 26 is secured to an arm 29 which is fulcrumed at 29' in a bearing block 31 at the free end of a support whose members 30 are laminated springs. The holders 24 and 25 are connected to the secondary coil of 35 transformer 19 by conduits 21.

The fixed electrode 27 is arranged in parallel relation to, and at a short distance from, the optical axis of a reflector 28 in the casing 2. The reflector has an elongated aperture 47 so that the electrodes 26 and 27 are free to move when the cowl 3 is turned about its hinge 14.

An arm 32' with a balance weight 32 at its free end, is secured to the holder arm 29, the balance weight being so determined that the weight of the electrode 26, its holder 24, and the arm 29, is 45 only partly balanced.

The springs 30 have a certain initial tension which moves them against an adjustable stop 30' in a bracket 30'' below the springs 30. A shaft 40, with a knurled handle 41 at its outer end, is mounted to rotate in the frame 3'. A cam 38 is secured on the shaft 40, and a spring 39 whose free end is connected to a short arm on the shaft 40, tends to turn the shaft anti-clockwise. An 50 arm 33, with a sector 34 at its free end, is connected to the arms 29 and 32', and is supported by a brake block 36 at the end of a laminated spring 37 which, in turn, is supported by the cam 38.

In the position of parts illustrated in Fig. 3, the cam 38, through the means described, holds the 55 spring frame 30 in elevated position and the free end of electrode 26 is at some distance from that of the fixed electrode 27. To strike the arc between the two electrodes, the handle 41 is turned clockwise, the sector 34 is released by the brake block 36, and the only partly balanced weight of the electrode 26 moves the end of this electrode against the end of electrode 27. The arc is now struck and then the handle is released to allow the cam and the brake block to again elevate the 60 sector under the action of spring 39.

Referring now to Fig. 4, each electrode, for in-

stance 26, as shown, has a hollow body of carbon, and a core 43. The core consists of one of the substances mentioned in the introduction, or a mixture of such substances, which produce a spectrum similar to the sun's, and preferably the 5 composition of the core 43 is such that ultraviolet rays are produced. The desirable current density of 0.26 amp. per square millimetre of electrode cross-section is obtained by suitable resistances, not shown. 10

As mentioned, the reflector should be so designed that a maximum illuminated area of practically uniform light intensity is obtained independently of the distance of the arc from the reflector. To this end a reflector 50, as shown in 15 Figs. 5 and 6, is built up from plane, sector-shaped mirrors arranged concentrically to the axis of the reflector, and at an angle to each other. As also mentioned, the mirrors 44 are made with non-reflecting areas. In the reflector 50, each 20 mirror 44 has a slot 45 whose sides diverge toward the optical axis of the reflector.

The plane mirrors 44 make up together a hollow pyramid with the elongated aperture 47 already described with reference to the reflector 28 25 in Fig. 3.

Instead of providing diverging slots 45, as shown in Figs. 5 and 6, each mirror, as shown for the reflector 51 in Fig. 7, is provided with a set of radially arranged circular holes 46, whose diameter 30 gradually increases toward the optical axis of the reflector.

It is understood that instead of providing slots, or holes, in the individual mirrors 44, bodies of 35 non-reflective material may be placed on the mirrors in any suitable way.

Preferably, the reflector should have 8 to 20 mirrors 44. The best effect is obtained with 12 mirrors.

By providing the means described on the mirrors, the amount of light reflected remains substantially constant notwithstanding the variable distance of the arc from the reflector as the electrodes burn down.

We claim:

1. In a portable electric irradiator, a reflector including a set of plane sector-shaped mirrors arranged concentrically to the optical axis of the reflector and at an angle to each other, and defining each a plurality of holes whose size increases 40 toward the optical axis of the reflector, and a pair of electrodes extending through the reflector. 50

2. In a portable electric irradiator, a transformer casing, a transformer in the casing, a reflector casing adjustably mounted on the transformer casing, a reflector in the reflector casing having an elongated aperture, an electrode cowl hinged to the reflector casing, a fixed electrode secured in the cowl and extending through the elongated aperture in the reflector, a spring frame in the 60 cowl, a movable electrode fulcrumed on the spring frame and also extending through the elongated aperture in the reflector, means for elevating the spring frame against its elastic reaction to move the movable electrode away from the fixed one, 65 automatic means for moving the elevating means into active position, manually operated means for releasing the spring frame to lower the movable electrode toward the fixed one, and conduits connecting both electrodes to the transformer. 70
